CARTON AND BLANK FOR FORMING THE
SAME

Harry F. Waters, New York, N. Y.

Application February 7, 1939, Serial No. 255,030

5 Claims. (Cl. 229—14)

This invention relates to the packaging of materials and, more particularly, to a carton or container having secured thereto a bag of improved construction, said carton or container being so constructed that it may be shipped flat to the purchaser and set up or squared into filling position by pressure exerted on opposed panels thereof.

One object of this invention is to provide a carton or container formed from an integral blank of flexible fibrous material having secured thereto along the side wall-forming panels a liner made preferably of thermoplastic liquid-proof material or provided with a coating of such material. The bottom-forming panel is provided with a medial fold line so that the front and rear panels may be brought into superimposed relation and the liner may be similarly folded. The side wall-forming panels are sealed in a flat position or they may be provided with securing means which can readily be fastened by the user when the carton or container is set up.

Another object of this invention is to seal the longitudinally disposed edges of the superimposed sections of the liner at the time the carton blank is folded upon itself and before the side wall-forming panels have been secured together. The carton and liner construction of the present invention obviates both a separate bag-forming operation and the use of complicated and expensive equipment in setting up the carton or container and the bag into filling position.

Still another object of this invention is to so secure the liner to the carton blank that it will open into filling position automatically when the carton is set up. At the same time the corners of the bag formed from the liner are free to move with respect to the corners of the carton so that should the package be dropped on one of its corners the bag, being free to move, will not be torn.

These and other objects of this invention will become more apparent from a study of the following description and by reference to the accompanying drawing in which:

Fig. 1 is a plan view of a carton blank having secured thereto an inner liner or member which forms the inner bag or container;

Fig. 2 is a view in perspective of the package formed from the blank of Fig. 1;

Fig. 3 is a plan view corresponding to Fig. 1, but showing a modified form of blank; and

Fig. 4 is a view in perspective of the package formed from the blank of Fig. 3;

Referring now to the drawing in which like numerals indicate like parts, and, more particularly to the modification disclosed in Figs. 1 and 2, there is shown a box blank 10 in which is secured, by parallel lines of adhesive 12 and 13, a liner or inner container-forming member 11. The blank, as is customary in the art, may be formed from any suitable flexible fibrous material such as chip board, kraft board, jute or the like. The type of material from which the liner 11 is formed depends primarily upon the material to be packaged. If liquid or semi-liquid materials are to be packaged, any suitable form of liquid-proof material will be employed as, for example, paper coated with commercial liquid-proofing material, rubber hydrochloride, sheeted resins, proteins, etc. Grease-proofed and wax or other coated materials as well as laminated sheet materials can be used. The use of any thermoplastic coating or material in addition to those materials above enumerated is also contemplated.

Although reference will hereinafter be made in the description to front and rear walls or panels, side walls or side panels, etc., it will be obvious that these terms are merely chosen for descriptive purposes and not by way of limitation, as the relative positions of the various walls and their sizes may be modified without departing from the scope of the invention. The blank 10 is, therefore, divided by the horizontally disposed score lines 14 and 15 into panels 16 and 17 which form the front and rear walls of the carton, and a bottom panel 18 which forms the bottom thereof. The bottom panel is also provided with a medial score line 18' along which the blank is folded, as will hereinafter be more particularly described.

Flaps 19 and 19' are attached to the longitudinal marginal edges of the rear panel 17 along score lines 20 and 21 and complementary, flaps 22 and 23 are attached to the longitudinal marginal edges of the front panel along extensions of these score lines. When the carton is set up the side walls thereof are formed by the flaps 19, 22 and 19', 23 which are held in overlapping fixed relation by the insertion of the tabs 24 and 25 carried, respectively, by flaps 19 and 19' into slots 26 and 27 formed, respectively, in the score lines separating flaps 22 and 23 from the front panel.

In order to complete the formation of the bottom, the flaps 19 and 19' have attached thereto, adjacent the bottom panel, bottom closure flaps

28 and 29 which are folded against the bottom after the latter has been squared or set up as illustrated in Fig. 2.

The carton is provided with the usual form of top closure flaps. Closure flap 30 is attached to the free end of the front panel along score line 31. The side closure flaps 32 and 33 are attached to the upper ends of the flaps 19 and 19' along score line 34 and the back closure flap 35 is attached to the upper end of the back panel along the same score line.

The liner 11, as has been previously described, may be provided with a liquid-proof thermoplastic coating or may comprise a sheet of thermoplastic material laminated to paper, sheeted cellulose, etc., or it may comprise an inherently liquid-proof and thermoplastic sheet. The liner is secured to the box blank by parallel lines of adhesive 12 and 13 which, however, do not extend completely to the ends of the flaps 19 and 19' for a purpose to be later described.

In setting up the combined liner and blank, the front panel is folded against the back panel by folding the blank along the score line 18'. The liner 11 being secured to the front panel 16 (or, stated in other words, the liner is secured to the panels 22 and 23 carried thereby), is also folded so as to bring one half thereof into contacting superimposed face relation with the other half. The longitudinal marginal edges are then sealed together, for example, by the application of heat and/or pressure and the package in flat form is ready to be shipped to the user.

To set up the container for filling, pressure is exerted along the longitudinal edges of the folded blank so as to force the two sections of the bottom into a single plane and to bring the front and rear forming panels into their normal operative position. In considering the relative dimensions of the side-forming panels and the location of the lines of adhesive 12, it will be noted that the panels 22 and 23 are substantially one-half the width of the panels 19 and 19', and the outer longitudinal marginal edges of the lines of adhesive 12 do not extend beyond the outer edges of panels 22 and 23 when the blank is folded along the score line 18'. There will be little or no relative movement between the edges of panels 22 and 23 with respect to the body portions of the panels 19 and 19'. Consequently when an inward pressure is exerted on the longitudinal marginal edges of the panels 19 and 19', the panels 22 and 23 will be folded into a plane normal to the plane of the front panel, with the subsequent folding of the panels 19 and 19' into a plane normal to the plane of the rear panel. Further, since the bag formed from the liner is secured to the panels 16 and 11, by the lines of adhesive 12 and 13, the bag will be automatically opened up for filling. Tabs 24 and 25 are then inserted into the slots 26 and 27. Bottom flaps are folded against the bottom of the carton and are secured thereto by adhesive in order to complete the carton.

After the bag 39 has been filled, opposite wall portions are then brought together and sealed in any suitable manner. This sealed end 40 is then folded against the contents and the tabs 41 and 42 formed by this folding operation are also folded against the contents. The flaps of the carton are then closed in the usual manner.

Referring now to Figs. 3 and 4 there is shown a liner and carton blank combination quite similar to that shown in Figs. 1 and 2, excepting that the

carton blank is so scored that a six-sided container may be formed. The carton blank is divided by the horizontally positioned score lines 46 and 47 into front and rear panels 43 and 44 and a bottom panel 45. The side forming panels 48 and 49, and 50 and 51, are attached respectively to the front and rear panels 43 and 44 along the longitudinally disposed score lines 52 and 53. Panels 50 and 51 have attached thereto adjacent the bottom panel 45, the bottom closure flaps 54 and 55 and are provided at the other end with the side closure flaps 56 and 57. Front and rear top closure flaps 58 and 59 are carried respectively by the front and rear panels 43 and 44. The liner is secured to the front and rear wall-forming panels by bands of adhesive 61 and 50' and 51'. These bands of adhesive are positioned adjacent the score lines 52 and 53.

As in the modification disclosed in Figs. 1 and 2, the blank is folded along the medial score line 62 provided in the bottom. Since the liner 63 is attached to both the front and rear wall-forming panels, it will automatically be folded at the same time that the carton blank is folded along the medial score line 62, and when so folded the upper and lower halves of the liner will be in substantial registration. The said wall-forming flaps 50 and 51 are each provided with a centrally located, longitudinally positioned score line 64 which divides the said panels into secondary panels 60.

After the blank has been folded along the score line 62 so that the lower half of the blank is superimposed on the upper half thereof, the liner is formed into a container by securing the longitudinal edges together. If the liner is formed from thermoplastic material or comprises sheet material provided with a thermoplastic coating, the edges may be secured together merely by the application of heat and/or pressure. Should the sheet material be provided with a non-thermoplastic coating or should an uncoated sheet material be used, adhesive may be used to form the longitudinally positioned seams of the inner container. The formation of the inner container is readily accomplished since the liner is sufficiently wide to project a substantial distance beyond the outer edges of the panels 48 and 49. After the inner container has been formed the panels 60 are folded along the score lines 64 so as to bring them into contact with the panels 48 and 49. The panels 48, 49 and 60 are thereupon secured together in any suitable manner as by the use of adhesive. When the panels 60 are folded over into sealing position the side seams of the inner container will be interposed between said panels and the panels 48 and 49. The combined carton and container in its flat folded form is then ready for shipment to the user.

As will be noted from an inspection of both Figs. 1 and 3, the liners are secured to the respective blanks by lines of adhesive which terminate short of the flaps by which they are carried. This feature of the present invention serves to allow the corners of the filled bag to move freely with respect to the corners of the carton. Should the carton be dropped or fall on one of the corners, the bag, being free to move, will not be torn nor will the bag seams be ruptured.

It will be further appreciated that although the bands of adhesive in both embodiments of the invention are carried by the front and rear wall-forming panels, they may, nevertheless, also be carried by the side wall-forming panels provided that they are located adjacent to the score lines separating the front and rear wall-form-

ing panels from the side wall-forming panels so that when pressure is exerted on the side-walls there will be not only a parallel separation of the front and rear wall-forming panels, but the side wall-forming panels will be squared up into a plane normal to the bottom. Such movement of the wall-forming portions of the container will automatically open the inner container into filling position.

While the features of the present invention have been described with respect to two forms of packages, it will be obvious to those skilled in the art that many types of material may be used in the manufacture of both the bag and carton and that many modifications may be made in constructional details thereof without departing from the spirit or scope of the invention except as hereinafter defined in the appended claims which are to be broadly construed.

I claim:

1. A container in flat folded form capable of being erected into a rigidly squared condition for filling, which comprises a pair of main panels in substantial registry; a pair of side panels folded along medial fold lines, and a bottom panel folded along medial fold lines and connecting said main panels; and bottom flaps folded along medial fold lines and extending from the lower ends of said side panels and defined by fold lines extending transversely of said medial fold lines, said flaps being foldable along said transverse lines when the container is erected to bring said flaps into facewise contact with said bottom panel and securable in such position to form stiffening ridges along said transverse fold-lines, thereby preventing collapse of the erected container along said medial fold lines.

2. A container in flat folded form capable of being erected into a rigidly squared condition for filling, which comprises a pair of main panels in substantial registry; a pair of side panels folded along medial fold lines, and a bottom panel, folded along medial fold lines and connecting said main panels; and bottom flaps folded along medial fold lines and extending from at least one of said medially folded panels and defined by fold lines extending transversely of said medial fold lines, said flaps being foldable along said transverse lines when the container is erected to bring said flaps into facewise contact with at least one panel having medial fold lines therein other than the panel from which each bottom flap extends and securable in such position to form stiffening ridges along said transverse fold lines, thereby preventing collapse of the erected container along said medial fold lines.

3. A container in flat folded form capable of being erected into a rigidly squared condition for filling, which comprises a carton, formed of fibrous, form-sustaining material having a pair of main panels in substantial registry, a pair of side panels folded along medial fold lines and a bottom panel folded along medial fold lines and connecting said main panels, said carton being erectable by unfolding said medially folded side and bottom panels; an inner flexible container secured to said carton on two opposed panels whereby when said carton is erected from its flat folded form the inner container will simultaneously open into filling position; and bottom flaps folded along medial fold lines and extending from the lower end of said side panels and defined by fold lines extending transversely of

said medial fold-lines, said flaps being foldable along said transverse lines when the carton is erected to bring said flaps into facewise contact with said bottom panel and securable in such position to form stiffening ridges along said transverse fold-lines, thereby preventing collapse of the erected container along said medial fold lines.

4. A container in flat folded form capable of being erected into a rigidly squared condition for filling which comprises a carton formed of fibrous, form-sustaining material having a pair of main panels in substantial registry, a pair of side panels folded along medial fold lines and a bottom panel folded along medial fold lines and connecting said main panels, said carton being erectable by unfolding said medially folded side and bottom panels; an open-mouth bag within said carton, said bag being formed of flexible sheet material folded upon itself along a line substantially coinciding with the medial fold of said bottom panel and having side seams, opposed walls of said bag being secured to opposed panels of said carton whereby when said carton is erected from its flat folded form said bag will simultaneously open into filling position with the bottom thereof substantially conforming to the bottom of said carton; and bottom flaps folded along medial fold lines and extending from the lower ends of said side panels and defined by fold lines extending transversely of said medial folds, said flaps being foldable along said transverse lines when the carton is erected to bring said flaps into facewise contact with said bottom panel and securable in said position to form stiffening ridges along said transverse fold lines, thereby preventing collapse of the erected package along said medial fold lines.

5. A container in flat folded form capable of being erected into a rigidly squared condition for filling which comprises a carton formed of fibrous, form-sustaining material having a pair of main panels in substantial registry, a pair of side panels folded along medial fold lines and a bottom panel folded along medial fold lines and connecting said main panels, said carton being erectable by unfolding said medially folded side and bottom panels; an open-mouth bag within said carton, said bag being formed of flexible sheet material presenting at least one fusible surface, said flexible sheet material being folded upon itself along a line substantially coinciding with the medial fold of said bottom panel and having side seams formed by fusion of said fusible surface in facewise contact with itself, opposed walls of said bag being secured to opposed panels of said carton whereby when said carton is erected from its flat folded form said bag will simultaneously open into filling position with the bottom thereof substantially conforming to the bottom of said carton; and bottom flaps folded along medial fold lines and extending from the lower end of said side panels and defined by fold lines extending transversely of said medial folds, said flaps being foldable along said transverse lines when the carton is erected to bring said flaps into facewise contact with said bottom panel and securable in such position to form stiffening ridges along said transverse fold lines, thereby preventing collapse of the erected package along said medial fold lines.

HARRY F. WATERS.
